UNITED STATES PATENT OFFICE.

GEORGE E. BLAINE, OF COSHOCOTON, OHIO.

SEAT-SPRING FOR VEHICLES.

SPECIFICATION forming part of Letters Patent No. 708,115, dated September 2, 1902.

Application filed January 30, 1902. Serial No. 91,874. (No model.)

To all whom it may concern:

Be it known that I, GEORGE E. BLAINE, a citizen of the United States, residing at Coshocton, in the county of Coshocton and State 5 of Ohio, have invented certain new and useful Improvements in Seat-Springs for Vehicles; and I do declare the following to be a full, clear, and exact description of the invention, such as will enable others skilled in the art 10 to which it appertains to make and use the same.

The invention relates to seat-springs for vehicles.

The object of the invention is to provide a 15 spring of this character which shall be simple of construction, durable in use, comparatively inexpensive of production, efficient in action, and by means of which the springs may be easily and quickly adjusted to the 20 seat to enable the seat to be engaged with wagon-boxes of different widths, and, furthermore, to provide means for attaching the spring to the wagon-box, which means will permit of the seat being swung upwardly and 25 forwardly and also when the seat is in position for use prevent it from shifting longitudinally of the wagon-box.

With these and other objects in view the invention consists of certain novel features 30 of construction, combination, and arrangement of parts, which will be hereinafter more fully described, and particularly pointed out in the appended claims.

In the accompanying drawings, Figure 1 is 35 a perspective view of the forward end of a wagon-box. Fig. 2 is a similar view with the seat swung upwardly and forwardly. Fig. 3 is a detail top plan view of the spring. Fig. 4 is a side elevation of the upper edge of the 40 wagon-box, the ends of the seat, and the spring, showing the relative arrangements of parts when the seat is in position for use; and Fig. 5 is a detail perspective view of the clasp.

Referring to the drawings, 1 denotes the 45 wagon-box, and 2 the seat. These parts may be of any well-known or approved construction.

3 denotes the springs, each of which preferably consists of a single length of spring- 50 rod bent intermediate its ends to form coils 4, the ends of which terminate in oppositely-projecting arms 5, formed with hooks 6. The

forward hook 6 engages a bracket-eye 7, secured to the upper edge of the wagon-box, and the rear hook loosely engages the upper 55 edge of the wagon-box and permits of the seat being swung forwardly. That portion of the spring - rod intermediate the coils is bent sharply at an angle to produce the arms 8, which are parallel and flush with the upper 60 surface of the coils and with the coils are adapted to engage the under side of the seat. A narrow loop 9 is formed at the ends of these arms and projects inwardly and also engages the under side of the seat. 65

10 denotes a clasp having upwardly-projecting points 11. This clasp is adapted to engage the side pieces of the loop and to be embedded in the lower side of the seat, and is held in position by a screw 12, which passes 70 through the clasp and between the members of the loop. By loosening this screw the loop of the spring may be moved inwardly or outwardly to adapt the seat to wagon-bodies of 75 different widths without the necessity of disconnecting the springs from the seat. The sharp bend *a* in the spring to form the arms 8 acts as a fulcrum for the spring, so that the entire resiliency takes place at the coils and not throughout that portion of the spring 80 of which the arms 8 and loop are formed, so that there will be no tendency whatever to pull or tear the spring from its fastening connecting it to the bottom of the seat.

It will be noticed that by reason of pivot- 85 ally connecting one end of the spring to the wagon-box and loosely connecting the other end so as to permit it to be disengaged therefrom the seat may be quickly and easily swung upwardly and forwardly, as is often- 90 times desired, and, furthermore, by reason of this pivotal connection the seat is prevented from creeping or sliding lengthwise of the wagon-box and remains in proper position when in use. 95

From the foregoing description, taken in connection with the accompanying drawings, the construction, mode of operation, and advantages of the invention will be readily understood without requiring an extended explanation. 100

Various changes in the form, proportion, and details of construction may be made within the scope of the invention without

departing from the spirit or sacrificing any of the advantages thereof.

Having thus described my invention, what I claim, and desire to secure by Letters Patent, is—

1. The combination with a seat, of a spring consisting of two coils terminating in arms adapted to engage the upper edge of the wagon-box, and a second set of arms leading from said coils and lying in the same horizontal plane as the upper portions of the coils and formed with a loop, the upper surface of said coils, the last-named arms and the loop contacting with and supporting said seat, and means for adjustably connecting said loop to said seat, said means comprising a clasp surrounding the sides of the loop and having its ends embedded in the lower side of the seat, and a screw passed through said clasp between the sides of the loop and into said seat, substantially as set forth.
2. The combination with a wagon-box and a seat, of a spring consisting of two coils ter-

minating in arms, one of which is pivotally connected to the upper edge of the side of the wagon-box, and the other of which has a loose hook engagement therewith, said springs being provided with a second set of arms lying in a horizontal plane and parallel with the upper portion of the coils and terminating in a loop, and means for adjustably connecting said loop to said seat, said means comprising a clasp surrounding the sides of the loop and having its ends embedded in the lower side of the seat, and a screw passed through said clasp between the sides of the loop and into the seat, substantially as set forth.

In testimony whereof I have hereunto set my hand in presence of two subscribing witnesses.

GEO. E. BLAINE.
